CLAIM

The ornamental design for a hand shower holder, as shown.

DESCRIPTION

FIG. 1 is a perspective view showing the front, left side, and top of the hand shower holder embodying my new design;

FIG. 2 is a front elevational view thereof;

FIG. 3 is a left side elevational view thereof;

FIG. 4 is a bottom view thereof;

FIG. 5 is a rear view thereof;

FIG. 6 is a left side elevational view thereof; and,

FIG. 7 is a top view thereof.

FIG. 1

FIG. 2

FIG. 3

FIG. 4

FIG. 5

FIG. 6

FIG. 7
